(57) **CLAIM**

The ornamental design for a desk with monitor stand, as shown and described.

DESCRIPTION

FIG. 1 is a perspective view of a desk with monitor stand showing my new design;

FIG. 2 is a front view thereof;

FIG. 3 is a rear view thereof;

FIG. 4 is a right side view thereof, the left side view thereof being a mirror image;

FIG. 5 is a top view thereof;

FIG. 6 is a bottom view thereof;

FIG. 7 is a perspective view thereof shown in an alternate position of use; and,

FIG. 8 is a perspective view shown in a manner of use. The broken line showing of the monitors in FIG. 8 is for the purpose of illustrating environment and forms no part of the claimed design.

1 Claim, 7 Drawing Sheets
